AMMUNITION BELT

Leslie Contardi, 4346 N. 19th Place, Milwaukee, Wis.

Filed June 15, 1962, Ser. No. 70,563

Term of patent 14 years

(Cl. D30—1)

FIGURE 1 is a perspective view of an ammunition belt embodying my new design;

FIGURE 2 is a front elevational view of the ammunition belt of FIGURE 1;

FIGURE 3 is a top plan view thereof; and

FIGURE 4 is a rear elevational view thereof.

The conventional buckle element is shown in broken lines, while the broken lines on the superimposed portion in FIGS. 1 and 2 and in the center rear of the belt as shown in FIG. 4 are intended to represent stitching.

I claim:

The ornamental design for an ammunition belt, as shown and described.
